UNITED STATES PATENT OFFICE.

HARRY CAMPBELL BRENEMAN, OF CINCINNATI, OHIO, ASSIGNOR TO THE CAPITOL SHADE ROLLER COMPANY, OF CINCINNATI, OHIO, A CORPORATION OF OHIO.

PAPER SHADE ROLLER AND METHOD OF FORMING.

Application filed May 3, 1921. Serial No. 466,498.

To all whom it may concern:

Be it known that I, HARRY C. BRENEMAN, a citizen of the United States, and residing at Cincinnati, in the county of Hamilton 5 and State of Ohio, have invented a new and useful Improvement in Paper Shade Rollers and Methods of Forming, of which the following specification is a full disclosure.

My invention relates to a window-shade 10 roller and the process of making the same. Such rollers are ordinarily wooden and the object of my invention is to produce a window shade roller made entirely of paper, which is cheaper and lighter than wood and 15 which at the same time shall have durability, rigidity, water-resistance surface, and the essential properties of a wood roller combined with the desirable characteristics of a paper structure.

20 The features of the invention, disclosing the underlying principles of the construction and method, are illustrated in the accompanying drawings, forming a part of this specification, wherein:

25 Fig. 1 is a diagrammatic representation of a sheet of pulp paper, the grain of the same being represented by dash lines.

Fig. 2 is a similar view showing the edge 30 of the paper inserted within a slotted mandrel, preparatory to rolling.

Fig. 3 is an end view of Fig. 2.

Fig. 4 is an end view of the rolled sheet.

Fig. 5 is an elevation of Fig. 4.

35 Fig. 6 is a diagram of a drying tray, illustrating the method of placing the rolled tubes, when drying, to prevent warping.

Fig. 7 represents a finished rolled paper shade roller made according to the herein- 40 described method.

The problem encountered, when it was proposed to substitute paper for wood, was to produce a roller of sufficient length for the purpose, say 36 inches, which would be entirely straight and cylindrical, sufficiently 45 rigid longitudinally, durable or permanently fixed with a suitable water resistance surface.

The first and essential consideration is to 50 employ a paper which will be relatively flexible in one direction and relatively non-flexible in the transverse direction and to roll the same upon a suitable mandrel transversely in relation to the direction of greater flexibility.

55 The invention is not limited to the con-

stituency of the paper, but the essence of characteristic indicated, for instance, will be found in a paper, say, suitable for paper-boxes or wall-board, formed of chipboard and pulp, in which the grain is to a great 60 extent laid uniformly by the rolls in the direction of issue from the paper machine. It is rolled so that the grain alignment runs parallel to the axis, that is, in the direction in which the paper is relatively more flexible. 65 This characteristic can best be indicated in Fig. 1, wherein the dash lines *a* indicate the direction of grain alignment corresponding to the direction in which the paper issues from the paper mill rolls, and the arrow *b* indicates the direction in which the paper is rolled on the mandrel to form the shade roller, that is to say, the dash lines *a* indicate the lay of the grain. Such a paper as is commercially known as reenforced chipboard will answer the purpose, and as explained, this paper is to be rolled 70 on an axis transversely to the line of issue from the machine.

The second step in the process consists in 75 rolling upon a hollow mandrel, shown in Fig. 2, preferably formed with a radial slot 2. The inner margin of the roll is tucked uniformly into this slot, and an adhesive coating is applied to the paper leaving a 80 non-adhesive marginal portion at the initial end of the paper sufficient to allow for the length of paper to be inserted into a mandrel slot and to roll at least once around the mandrel so that the paper will not adhere 85 to the mandrel. The paper so laid out, is rolled upon this mandrel for its full length with the grain of the paper lengthwise with the axis of the mandrel, bringing the edge of the last lap in a straight line with the 90 axis of the mandrel. The plies are made in rolling or coiling the paper, each arm adhesively secured one to the other, the adhesive rendering the tube when completed in a moist state which is required to be dried. 95

It has been found that great care must be exercised in drying the tubes or rolls, as they invariably become warped and crooked in drying.

I have discovered that if these rolls are 105 contactually superposed in a dry room or on drying trays that they will warp and remain crooked. Therefore, a step of my process consists in supporting these rolls or tubes in horizontal rows vertically spaced 110

from one another. It take about a week to properly dry the tubes if subjected to a temperature approximately 80° to 90°, slow, even drying. The tubes will bend or distort during the process, but I have found that when so separated, they entirely right themselves at the end of the drying period.

One of the great difficulties has been to roll tubes of this length entirely true, so that the outer edge of the paper will lie in a straight line. This is accomplished by the slotted mandrel which enables one to insert a definite length of the paper strip at the beginning of the operation, say, half an inch, uniformly throughout its width.

When so dried, the tubes are preferably surfaced with a water resistance coating and preferably stained or colored. I have found best for this purpose the water solution of a selected aniline dye with preferably sufficient casein to form a saturated solution. When the roll is so formed, the ferrules 3 are forced on to the opposite ends.

I have found this roll very durable and permanent. It is both light and rigid and a very great improvement over the ordinary wood roller.

Having described my invention, I claim: 30

The herein described process of forming a window shade roller which consists in rolling upon a mandrel a strip of paper with the grain running parallel to the axis, inserting a uniform marginal portion of the strip radially into a mandrel roll, adhesively coating the paper strip except the insert portion and sufficient to non-adhesively envelop the mandrel, drying the rolls while supported in horizontal rows vertically 35 spaced from one another, and finally surfacing the dried roll with a water-resisting material.

In witness whereof, I hereunto subscribe my name, as attested by the two subscribing 45 witnesses.

HARRY CAMPBELL BRENEMAN.
